UNITED STATES PATENT OFFICE.

DORA HARRISON, OF LANSING, MICHIGAN, ASSIGNOR TO THE HARRISON MANUFACTURING COMPANY, OF GRAND RAPIDS, MICHIGAN.

BOSOM-PAD.

SPECIFICATION forming part of Letters Patent No. 599,180, dated February 15, 1898.

Application filed April 22, 1897. Serial No. 633,352. (No model.)

To all whom it may concern:

Be it known that I, DORA HARRISON, of Lansing, in the county of Ingham and State of Michigan, have invented new and useful 5 Improvements in Bosom-Pads, of which the following is a full, clear, and exact description.

The invention relates to bosom-pads such as shown and described in the Letters Patent 10 of the United States No. 579,824, granted to me on March 30, 1897.

The object of the present invention is to provide a new and improved dress-form which is simple and durable in construction, readily 15 applied to or removed from the pockets of corsets and other garments, and designed to insure a proper fitting of the dress and to supply natural deficiencies.

The invention consists of certain parts and 20 details, as will be fully described hereinafter and then pointed out in the claim.

Reference is to be had to the accompanying drawings, forming a part of this specification, in which similar characters of reference indicate 25 corresponding parts in both the figures.

Figure 1 is a front elevation of the improvement, and Fig. 2 is a sectional plan view of the same.

The improved dress-form is provided with 30 the two inflatable pads A A', made of thin rubber and rendered non-odorous by special treatment. Each of the pads A A' is formed with a comparatively flat back A², and the semispherical fronts A³ are formed at their 35 adjacent bases with outwardly-extending flanges A⁴, cemented together and covered by an annular welt A⁵, of rubber, and made U-shaped in cross-section to completely inclose the said flanges A⁴, as plainly shown in 40 the drawings. The welt A⁵ forms a binding for the said flanges and is secured thereto by cement or other suitable adhesive substance.

On the outer sides of the pads A A' are arranged attaching-loops B, cemented or otherwise 45 secured to the welts A⁵, and the said loops

secure the dress-form within a shell, as shown in the patent above referred to. The dress-form may be attached directly to the corset or other garment by safety-pins, sewing, or the like. On the inner sides of the pads A A' 50 are arranged the flexible lace-arms C, cemented or otherwise secured to the welts A⁵ and formed with apertures for the lacing D to connect the two pads A A' with each other.

Each of the pads A A' is formed at its side 55 with a filling-tube E for inflating the corresponding pad by the wearer blowing into the filling-tube. After the pad is expanded to the desired degree then the end of the filling-tube is bent upon itself, and the thus doubled-up parts are fastened together by a small rubber band, cord, or string F to prevent escape of air and deflation of the pad when in use.

Now by the construction described it is evident that the pads A A', owing to the flat 65 backs A², fit snugly onto the body of the wearer, and the two pads can be placed a distance apart, according to the location of the natural breasts of the wearer, by adjusting the lacing D accordingly. The backs A², of 70 course, follow the shape of the natural breasts and extend inwardly into the fronts A³ when in use, as indicated by dotted lines in Fig. 2.

Having thus described my invention, I claim as new and desire to secure by Letters 75 Patent—

A bosom-pad having two pad-sections, each formed with a back and a front section having meeting edges provided with flanges lying snugly against each other, an annular welt 80 surrounding the flanges at each pad-section and cemented to the flanges to hold the same together, a lace-arm secured to the welt of each pad-section, and lacing adjustably connecting the lace-arms.

DORA HARRISON.
